DISPLAY CASE

Nathan Owitz, New York, N. Y., assignor to John C. Welwood Corp., New York, N. Y., a corporation of New York

Application April 13, 1931. Serial No. 529,668

1 Claim. (Cl. 206—72)

This invention relates generally to display cases and more particularly to cases for displaying bolts of ribbon and the like.

In many of the cases or racks with which applicant is aware, the articles to be displayed are placed in the case in the same horizontal position so that it is difficult to see them without looking directly down upon them. Other cases support the articles in an inclined plane but such articles tend to move downward by gravity coming into contact with the article next below it, and becoming soiled. In other cases the articles such as bolts of ribbon rest against their supporting surface and thereby become soiled. Other cases are so built that they gather dust and other foreign matter and are thus objectionable.

I overcome the foregoing objections by providing a case with rails or shelves that support the article to be displayed, no matter what the shape of same, in an inclined plane so that each article can be seen at a distance and to advantage and readily distinguished and recognized. When the article to be displayed is a bolt of ribbon, the rails only engage the paper portion of the bolt near each edge thereof so that the ribbon is held out of contact with any portion of the case. Devices are provided for holding each article in its fixed position preventing it from falling down on to the next article. A sign board is associated with the case for carrying advertising or other data.

In addition my improved case is simple in construction, inexpensive to manufacture and rugged in construction, dust and dirt proof and is adapted to be placed on any kind of supporting surface.

Other objects and advantages of my improved case will be apparent from the description thereto to follow taken in connection with the accompanying drawing in which—

Figure 1 is a perspective view of my improved case.

Figure 2 is a sectional view on the plane indicated by the line 1—1 of Figure 1.

Figure 3 is an enlarged detail sectional view taken on the plane indicated by the line 2—2 of Fig. 2.

Figure 4 is a modification showing a modified form of supporting rail.

Referring to the various views of the drawing, the improved case or rack comprises a frame shown as rectangular in the drawing but which may of course be of any desired shape. This frame includes a front wall 10, a rear wall 11,

the rear wall being preferably higher than the front wall. Joining the front and rear walls are side walls 13. All of these walls may be formed of cardboard, wood, metal or any suitable material sufficient to provide the necessary 60 rigidity as will be understood. The bottom edge of each wall is flat permitting the frame to be supported on almost any kind of a surface and such edges may be covered with cloth or other protective covering in order to protect the supporting surface. The upper surfaces of the side walls 13 are inclined downwardly from the rear to the front. When the walls are formed of cardboard as illustrated in the drawing, the lower and upper edges of all of the walls may be 70 protected by channel shaped members 14 formed of metal, which members also add to the attractiveness of the case.

The interior of the frame is divided by partitions 15 which form compartments 16 of various widths, the compartments illustrated decreasing in width from left to right. These compartments may of course be all of the same width if desired. Mounted on the side walls and partitions are supports, here illustrated as 75 shelves, rails or tracks 17. These rails 17 are supported in an inclined plane by L-shaped members 18 which may be made of wood or metal as desired. Cross pieces 19 of wood or metal may be placed underneath the shelves 80 or rails at spaced points in order to brace the same. The side walls 13 are braced by U-shaped members 20 crossing therebetween at their lower edges.

These rails are adapted to support articles for display purposes. In the drawing in Figure 1, the article shown is a cylindrical shaped bolt 21, formed of paper around which is wound the ribbon 22 which it is desired to display. The rails are mounted sufficiently close to the top edges of the side walls and partitions to permit a portion of the bolt and ribbon to protrude thereabove. It will be understood of course that any article having a body portion of sufficient width may be supported on these rails. When a bolt of ribbon is supported as illustrated, no portion of the ribbon touches the rails, only the edges of the paper bolt resting on the rails. The space between the rails 17 is open so that dust and dirt may pass therethrough to the surface supporting the case where it may be 90 readily removed.

An important feature of my invention is the provision of means whereby such articles may be displayed in an inclined plane and yet not 110

slide down from their proper position into contact with the next article below. This is accomplished by providing spaced stop members 23 which project outwardly from the side walls and partitions at opposite points into the compartments 16, and which are positioned above and adjacent to the rails 17 and adapted to engage the ends of the body of the bolt 21 supported on the rails. These stops are illustrated in the drawing as metal plates having one of their ends secured to the side wall 13 and passing through the partitions 15 so as to extend outwardly from each side thereof. While I prefer that these stops be permanently fixed as illustrated, it will be understood that they may be removably mounted in order to adjust the length of the spaces between adjacent stops as will be apparent. These stop members may be out-struck from the material forming the walls and partitions if desired.

With reference to the form of the invention shown in Figure 4, instead of having a continuous rail or shelf 17, the supporting means may be formed as a short shelf 24 formed with an integral upstanding flange 25 against which the bolt rests to prevent it from moving.

The case may be provided with an upright sign board 26 mounted detachably on the rear wall by means of pins 27 adapted to be inserted into

sockets 28 mounted on the rear wall. A card or sign for carrying advertising or other indicia may be removably mounted on this board adding greatly to the utility of the case.

While I have illustrated and described several forms of my invention changes in details might be resorted to without departing from the principle of the invention.

I claim:

In a display case, a rectangular frame consisting of vertical front, rear and side walls, a plurality of parallel partition walls within said frame having ends held on said front and rear walls for dividing said frame into a plurality of elongated open compartments, a pair of inclined rails on each partition wall extending longitudinally thereon on opposite sides and on opposite sides of each compartment, said rails forming means to support the margins of a bolt of ribbon wound thereon accommodating the ribbon on said bolt in the space between said rails, and stop members on said partition walls spaced from each other to accommodate a bolt of ribbon in the spaces between said stop members to hold said bolt in stationary position permitting unrolling of the ribbon therefrom in upward and downward directions without contact with any part of said display case.

NATHAN OWITZ.
